JOHN H. HOBSON, OF DANBURY, CONNECTICUT, ASSIGNOR TO THE HOBSON-BOTTS COMPANY, OF DANBURY, CONNECTICUT, A CORPORATION OF CONNECTICUT.

PROCESS OF MANUFACTURING TABLE KNIVES AND THE LIKE.

Application filed February 20, 1923. Serial No. 620,172.

To all whom it may concern:

Be it known that I, JOHN H. HOBSON, a citizen of the United States, residing at Danbury, Fairfield County, Connecticut, have invented new and useful Improvements in Processes of Manufacturing Table Knives and the like, of which the following is a specification.

This invention relates to a novel method 10 of producing implements such as kitchen-knives, table-knives, etc., which are made up of the implement proper and a solid handle rigidly and permanently secured together to constitute a single unitary article. 15 The invention comprises broadly the novel method of manufacturing such articles. The invention further comprises the various novel features and combinations of procedure and of structure which are hereinafter 20 set forth and claimed.

The invention will be best understood by reference to the accompanying drawings and the appended description, which disclose exemplifications of said invention as applied 25 to the manufacture of a table-knife. But the broad invention is not limited to that particular application nor to the particular steps of procedure or the particular features of structure hereinafter specified. In 30 these drawings—

Figs. I and II are respectively a face-view and an edge-view of a portion of a knife-blade with its tang and of the adjacent end of a handle-blank, the two members being 35 in position for assemblage but not yet assembled;

Fig. III indicates, in longitudinal vertical section, a pair of dies between which said handle-blank is inserted to be secured 40 to said tang and simultaneously forced into its final shape;

Fig. IV indicates the assemblage of said blade-tang and handle-blank, but not yet secured together, being a transverse section 45 taken on the line IV-IV of Fig. I;

Fig. V represents, by similar view, the same parts after being rigidly and permanently secured together;

Figs. VI, VII, and VIII are details, each 50 representing a modified form of knife-blade tang;

Figs. IX and X are details, each illustrating a modified form of the inner end of the handle-blank; and

55 Figs. XI and XII are respectively a face-

view and an edge-view of a portion of a completed table-knife.

In said views, the thickness of the knife-blade and tang is considerably exaggerated.

Referring first to Figs. I to V, 1 represents the implement proper, such as a knife-blade, one end thereof constituting an integral tang 2, which is shown as recessed on opposite edges as at 3-3 and provided with a hole, as 4. Said recesses and hole are to 60 serve as locking-features, and are preferably rectangular, although they may be round (circular). Said knife-blade and tang are indicated (with exaggerated thickness) as a flat unitary member of uniform thickness. 65 Said member is formed of relatively-hard metal, as by cutting-out or punching from a sheet or strip of hard steel; and the entire member, comprising said tang and said locking-features, is formed by the one operation. 70

5 represents a handle-blank, a flat unitary member of uniform thickness, substantially thicker than said blade and tang, and of the general contour desired for the finished handle; and it is formed of a relatively- 80 softer metal or metallic composition, preferably by punching it out from a relatively-thick sheet or strip of soft steel. In one end of said blank is then produced, as by sawing or milling, a slot or slit 6, of a size for 85 snugly receiving said tang 2. Preferably said tang has a squared rear end 2', and so has said slit, as indicated by the dotted line 6', whereby the two squared surfaces may abut and prevent any tendency to relative 90 edgewise-rocking of the assembled members.

7 and 7' are two complementary die-members, suitably concaved, to produce (when brought together) the desired contour of the completed handle. If preferred, 95 they may present, in reverse, any desired ornamentation or pattern to be imparted to the handle. The cavity enclosed by said die-members, when closed together, is preferably slightly less than the space occupied 100 by said handle-blank before compression.

The two members, 2 and 5, are assembled, as indicated in Figs. III and IV, and (at normal temperature, without being heated) are placed between said die-members 7 and 105 7' (also at normal temperature, and not heated), as indicated in Fig. III; and thereupon said die-members are forced together, as by a drop-hammer, whereby that single operation cold-swages or cold-welds the han- 110

dle firmly and permanently upon the tang and simultaneously cold-forces the handle-blank into the desired handle-shape and configuration, imparting thereto the desired 5 ornamentation. By this single operation some of the cold metal of the handle-blank is forced to engage the aforesaid locking-features, entering the hole 4 and filling the recesses 3--3, closing up the two sides of the 10 slit 6, and producing a rigid and permanent union which presents no seam or crack. Thereafter, any fin that may result (from the escape of some of the soft metal between the approaching faces of the dies) may be 15 ground off; and the edge of the blade may be sharpened, and the entire unitary implement or merely its handle cleansed and copper-plated, and then plated with nickel or silver if desired.

Such expressions as cold-swaging and cold-welding and cold-forcing, are intended merely to differentiate from a treatment where the temperature of the metal has been substantially raised, as in heat-welding and 20 in casting; and does not exclude the use of the dies whose temperature may have been raised by the use of the drop-hammer in swaging such handles upon such implements; and the word "cold" does not exclude 25 an article or die having a temperature substantially below that essential in heat-welding and in casting.

Referring next to Figs. VI-VIII, the 30 hole in the tang, instead of being rectangular, may be circular, as at 4', in Fig. VI; or it may be omitted altogether, as in Fig. VII. So, also, the recesses in the tang may be rounded (more or less semi-circular) or V-shaped, or may be omitted altogether, as 35 in Fig. VIII.

Referring next to Figs. IX and X, the handle-blank also may have a locking-feature, such as a hole 8 through its slit end, as in Fig. IX, or a recess 8' in the edges 40 of said slit, as in Fig. X, which locking-feature may be rectangular as shown, or rounded (circular), and is formed by the same punching operation that produces the blank itself. When the handle-blank has such locking-feature, the same is located to register with a locking-feature of the same shape in the tang, and a plug or rivet, such as 9 in Fig. X, is inserted into the registered holes, and the entire assemblage (slitted blank, knife-tang and plug) is then presented between the dies and subjected to the blow of the drop-hammer, by which the ends of said plug 9 are flattened out simultaneously with the other results already mentioned.

The above-described process is exceedingly simple and economical. It comprises merely the simple steps of punching-out the knife-blade and tang with its locking-features, and the handle-blank (with its

locking-feature, if desired, the simple step of slitting one end of said blank, the simple step of inserting the knife-tang into the slit (and inserting the plug, when used) and presenting the assembled members between the swaging-dies, and the simple step of imparting a blow of the drop-hammer, followed by grinding off any fin and finishing the completed article as desired. Consequently the table-knives or other articles produced by said process are far less expensive than similar articles produced by other processes, yet are just as good as those produced by more complicated and expensive operations, and have their handles so firmly and permanently secured as to be in effect one-piece or unitary articles.

The invention has thus been described in full detail as applied to the manufacture of a table-knife; but it must be distinctly understood that the broad invention comprises a far wider range of application and is not limited to the precise steps and order of procedure nor to the precise details of structure and combination which are hereinbefore set forth.

The invention having been thus fully described, what is claimed is:

1. The process of manufacturing a metallic implement having a softer metallic handle permanently and rigidly secured thereto, which consists of forming a solid handle-blank by punching it out from a thick sheet of such soft metal while simultaneously producing a locking-feature in one end thereof, then slitting that end of said blank, also forming the implement proper by punching it out from a thinner sheet of hard metal while simultaneously providing an integral tang having a locking-feature, next fitting said tang into said slit and thereby registering said locking-features, then fitting a metal plug into said registered locking-features, thereafter cold-swaging said members and plug while simultaneously cold-forcing said blank into the desired handle-configuration, and finally finishing the completed article as desired.

2. The process of manufacturing a metallic implement having a softer metallic handle permanently and rigidly secured thereto, which comprises punching-out from a thick sheet of such soft metal a handle-blank, then slitting one end of said blank, also punching-out from a sheet of hard metal the implement proper having an integral tang provided with a locking-feature, next fitting said tang into said slit, and then cold-swaging said handle-blank upon said tang while simultaneously cold-forcing some of said blank-metal into locking-engagement with said locking-feature and also simultaneously cold-forcing said blank into a predetermined handle-configuration.

3. The process of manufacturing an implement such as a metal-handled table-knife, which comprises punching-out from a thick sheet of soft steel a handle-blank, 5 then slitting one end of said blank, also punching-out from a thin sheet of hard steel a knife-blade having an integral tang provided with a locking-feature, next fitting said tang into said slit, then positioning said blank and tang between two suitable die-members and subjecting them to great pressure as by the blow of a drop-hammer. 10

15

10. The process of manufacturing an implement such as a table-knife, which comprises punching-out from a sheet of soft steel a handle-blank, then slitting one end 20 of said blank, also punching-out from a

thin sheet of hard steel a knife-blade having an integral tang, next fitting said tang into said slit, and then positioning said 25 blank and tang between two suitable die-members and subjecting them to great pressure as by the blow of a drop-hammer.

5. The process of manufacturing an implement such as a table-knife, which comprises forming from soft steel a solid handle-blank, then slitting one end of said blank, also punching-out from a sheet of hard steel a knife-blade having an integral tang, next fitting said tang into said slit, 30 and then positioning said assembled blank and tang between a single pair of suitable die-members and subjecting them to great pressure as by the blow of a drop-hammer, 35 by the single action simultaneously securing the parts together and imparting the desired handle-configuration. 40

JOHN H. HOBSON.
